ILLED BAG CLOSING UNIT

Norman V. Christensen, Chicago, Ill., assignor to
 Union Special Machine Company, Chicago, Ill.,
 a corporation of Illinois

Application April 23, 1937, Serial No. 138,589

REISSUED

JUN 4 1940

5 Claims. (Cl. 192—11)

My invention relates to a machine or unit for closing filled bags or sacks and the like, and especially to a self-contained mobile unit for this purpose, that is preferably suspended so that it can be pulled about and raised and lowered at will by an operator. Such freedom of movement of the unit allows it to be conveniently used to fasten shut the mouths of filled bags standing on a floor. I have illustrated and explained my novel unit as including a sewing machine for stitching the bag mouths, this being a preferred method of fastening them shut. Various features and advantages of the invention will appear from the following description of a species or form of embodiment, and from the drawings. All the features shown or described are of my invention, so far as novel over the prior art.

In the drawings, Fig. I is a side view of a suspended unit conveniently embodying my invention.

Fig. II is a plan view of the unit with certain accessories omitted.

Fig. III is a plan view of a thread stand, illustrating its attachment to the unit.

Fig. IV is a plan view of a guiding and manipulating handle.

As shown in Figs. I and II, the bag-closing unit comprises a fastening mechanism 10, such as any suitable type of sewing machine, and a bracket 11 secured thereto, and carrying an (electric) motor 12 for driving the machine 10. The unit is shown as suspended by a flexible cable 13 passing over a pulley sheave 14 and connected to a counterweight 15, so that the whole unit can be readily moved or adjusted up and down by the operator. The flexible cable 13 also allows the unit to be easily shifted horizontally to bring its sewing head 16, needle(s) 17, presser-foot 18, and arm 19 into proper relation to the superposed edges of a sack-mouth 20, and moved along the mouth to sew it shut. The needle 17 is shown in Fig. I as extending horizontally, while the arm 19 and the sewing machine drive shaft 21 extend vertically, or substantially so. The pulley sheave 14 is shown mounted in a swivel-bracket 22, which may be suspended in any suitable way from the ceiling,—or from a supporting carriage on an overhead track (not shown), if such mobility of the unit is desired. As shown in Figs. I and II, the cable 13 is attached to the bracket 11, being suitably secured in an upstanding hollow boss or sleeve 23 on said bracket. A thread-stand 25 is shown in Figs. I and III as clamped on the upper end of the boss 23: it carries two

cops of sewing thread 26 for the machine 10, and gallows-like guides 27 for the thread.

As shown in Figs. I and II, the usual base 30 of the machine 10 abuts against a vertical face of the bracket 11 and is secured thereto by a bolt 31. The motor 12 is movably mounted on a horizontal face of the bracket 11, with its driving shaft 32 (substantially) horizontal, and so as to swing horizontally relative to the bracket. The motor 12 is shown attached to a base plate 33 which is pivoted on the horizontal bracket face by a bolt 34 (substantially) parallel with the machine shaft 21. One end of the motor shaft 32 carries a (grooved) driving pulley 35 that is connected by a quarter-turn belt 36 to a (grooved) 15 driven pulley 37 on the upper end of the machine shaft 21. The shaft 21 is also provided with a brake drum 38, here shown as formed by a plain face of the pulley 37 beside its belt groove. It will be seen that as the motor 12 swings one 20 way or the other about its pivot 34, the belt 36 is tightened so as to drive the machine 10, or relaxed and loosened to leave it idle.

For the purpose of applying and releasing the braking means on the drum 38, and of relaxing 25 and tightening the belt 36, there is shown a vertical rock shaft 40, (substantially) parallel with the machine shaft 21, and mounted to turn in suitable bearings 41, 41 carried by arms 42, 42 on the bracket 11. The braking means here 30 shown consists of a brake-shoe or face 43 on an arm 44 fast to the upper end of the shaft 40, above its upper bearing 41. For swinging the motor 12, the shaft 40 has an arm 45 that is connected by a (turnbuckle) link-rod 46 to an 35 arm 47 on the motor, here shown as formed by a projecting portion of the plate 33. For convenient manual operation of the shaft 40, a handle 48 may be attached to its lower end. Just above this handle 48, there is a bearing bracket 49 for the shaft 40, attached to the (cylindrical) machine arm 19, and provided with a handle 50. These handles 48, 50 can be conveniently grasped by an operator and squeezed together, thereby releasing the brake 43 and swinging the motor 12 45 counter-clockwise (Fig. II) to tighten the belt 36 and drive the machine 10 from the motor. Provision is preferably made for automatically setting the brake 43 and relaxing the belt 36 whenever the operator releases the shaft 40 by relaxing his squeeze on the handles 48, 50. For this purpose, there is shown a helical torsion spring 55 around the shaft 40, above the lower bracket arm 42, with one end attached to said arm 42 and the other end attached to a collar 55

56 fast on said shaft. This spring 55 continually urges shaft 40, brake-arm 44, and motor 12 in a clockwise direction (Fig. II).

In using the unit, the operator shifts it about 5 horizontally or up or down by handle 50. When he is ready to close a bag mouth, he has only to squeeze handles 48 and 50 together, as already explained, and to move and guide the machine 10 along the bag mouth by these handles. The 15 position of the handles 48, 50 makes all this easy without the operator's changing his own position, or his grip on the handles. Besides braking and stopping the machine 10, the brake means 43, 44 serves as a stop to limit the belt-relaxing or loosening swing of the motor 12, so as to avoid throwing the belt off the pulleys 35, 37.

Having thus described my invention, I claim:

1. A flexibly suspended, freely movable outfit 20 for closing the mouths of filled sacks and the like, comprising a bracket, a fastening-machine mounted on said bracket with its driving shaft substantially vertical, a motor mounted on said bracket for movement relative thereto, a belt interconnecting the motor and fastening machine 25 shafts so as to be tightened to drive the machine, and relaxed to leave it idle, by movements of the motor relative to the bracket, a substantially vertical shaft and brake means for stopping the machine operated thereby, and means operated 30 by movement of said shaft to swing the motor and relax the belt when the brake is applied, and vice-versa.

2. A flexibly suspended, freely movable outfit 35 for closing the mouths of filled sacks and the like, comprising a bracket with bearing arms, a fastening-machine mounted on said bracket with its driving shaft substantially vertical, said shaft having thereon a pulley and a brake drum, a motor having a substantially horizontal pulley-equipped shaft and pivotally mounted on said 40 bracket to swing about an axis substantially parallel to said machine shaft, a belt interconnecting said motor and machine shaft pulleys so as to be tightened to drive the machine, and relaxed to leave it idle, by swinging movements of 45 the motor relative to the bracket, brake means for said brake drum, a substantially vertical, manually operable shaft mounted to turn in

said bearing arms of said bracket and operatively connected to said motor and brake means to release the brake and swing the motor to tighten the belt when the shaft is turned one way by an operator, and means for automatically applying 5 the brake and swinging the motor to relax the belt when the shaft is released by the operator.

3. A flexibly suspended, freely movable outfit 10 for closing the mouths of filled sacks and the like, comprising a bracket, a fastening-machine mounted on said bracket with its driving shaft substantially vertical, a motor mounted on said bracket for movement in a horizontal plane relative thereto, and having a substantially horizontal shaft, and a belt interconnecting the motor and fastening-machine shafts so as to be tightened 15 to drive the machine, and relaxed to leave it idle, by movements of the motor horizontally relative to the bracket.

4. A flexibly suspended, freely movable outfit 20 for closing the mouths of filled sacks and the like, comprising a bracket, a fastening-machine mounted on said bracket with its driving shaft substantially vertical, a motor mounted on said bracket for movement in a horizontal plane relative 25 thereto, and having a substantially horizontal shaft, a belt interconnecting the motor and fastening-machine shafts so as to be tightened to drive the machine, and relaxed to leave it idle, by movements of the motor horizontally relative to the 30 bracket, brake means for stopping the machine, and means for swinging the motor and thereby relaxing the belt when the brake is applied, and vice-versa.

5. A flexibly suspended, freely movable outfit 35 for closing the mouths of filled sacks and the like, comprising a bracket; a fastening-machine mounted on said bracket with its driving shaft substantially vertical; a motor movably mounted on said bracket with its shaft substantially horizontal, and swingable relative to the bracket in a horizontal plane; and a belt interconnecting the motor and fastening-machine shafts so as to be tightened 40 to drive the machine, and relaxed to leave it idle, by the horizontal swinging of the 45 motor relative to the bracket as aforesaid.

NORMAN V. CHRISTENSEN.
